UNITED STATES PATENT OFFICE

122,916

DESIGN FOR A MECHANICAL FIGURE

Blanche B. Burkitt, Alhambra, Calif.

Application June 17, 1940, Serial No. 93,047

Term of patent 3½ years

To all whom it may concern:

Be it known that I, Blanche B. Burkitt, a citizen of the United States, residing at Alhambra, in the county of Los Angeles, State of California, have invented a new, original, and ornamental Design for a Mechanical Figure, of which the following is a specification, reference being had to the accompanying drawing, forming part thereof.

In said drawing:

Fig. 1 is a side elevation;

Fig. 2 is a front elevation; and

Fig. 3 is a top plan view of a mechanical figure showing my new design.

I claim:

The ornamental design for a mechanical figure, as shown.

BLANCHE B. BURKITT.
